[57] CLAIM

The ornamental design for a crescent cut sole contour for golf clubs, as shown and described.

DESCRIPTION

FIG. 1 is a front perspective view of the crescent cut sole contour for golf clubs;

FIG. 2 is a front view thereof;

FIG. 3 is an end view thereof; and,

FIG. 4 is a side view thereof.

The broken line showing of an iron-type golf club is for illustrative purposes only and forms no part of the claimed design.
